(57) **CLAIM**

The ornamental design for a grip aid for a catheter, as shown and described.

DESCRIPTION

FIG. 1 is a perspective view of an embodiment of a grip aid for a catheter showing our new design;

FIG. 2 is a perspective view thereof;

FIG. 3 is a front plan view thereof;

FIG. 4 is a right side elevational view thereof;

The left side view, is a mirror image of the right side view.

FIG. 5 is a rear elevational view thereof;

FIG. 6 is a top plan view thereof;

FIG. 7 is a bottom plan view thereof; and,

FIG. 8 is a perspective view of the grip aid for a catheter demonstrating its placement with a catheter.

The broken lines in the figures are included for the purpose of illustrating environmental structure and form no part of the claimed design.
